UNITED STATES PATENT OFFICE

IRA J. CLARK, OF FORT MORGAN, COLORADO

VALVE LIFTER

Application filed November 14, 1931. Serial No. 575,121.

This invention relates to valve lifters of the C-type and including upper and lower members connected for adjustment toward and away from each other, means carried by the 5 upper member for engagement with the head of a valve, means carried by the lower member for engagement with the spring seat of the valve, and means by which the members may be adjusted toward each other to compress the spring of the valve and thus permit the removal of the pin or key by which the spring seat is supported on the stem of the valve.

The invention has for one of its objects to 15 provide a valve lifter of the character stated wherein the valve head engaging means will embody a push bar secured to and extending downwardly from the upper member, a foot piece and pin carried by the push bar 20 for relative upward and downward movement, the pin having a pointed lower end located centrally of and normally extending below the foot piece, and a spring carried by the push bar and acting to normally hold the 25 pin with its lower end below the foot piece, the pin being adapted to engage the head of a valve during the application of the lifter to center the foot piece on the valve head and hold it against accidental displacement there- 30 from during and after the adjustment of the lifter to compress the spring of the valve, and the foot piece being adapted during the adjustment of the lifter to move downwardly with respect to the pin into engagement 35 with the valve head.

The invention has for a further object to provide a valve lifter of the character stated wherein the foot piece and centering pin shall be adapted for engagement with valve heads 40 having flat, concave or convex upper sides.

The invention has for a further object to provide a valve lifter of the character stated wherein the push rod will be hollow to adapt 45 it to slidably receive the centering pin, wherein the foot piece will have a fixed position on the push rod, wherein the relative movements of the centering pin and foot piece will be limited, and wherein the spring for holding 50 the centering pin in normal position with

respect to the foot piece will be mounted within the push rod.

The invention has for a further object to provide a valve lifter of the character stated wherein the spring seat engaging means will 55 embody a pair of relatively spaced jaws which while strong enough to lift any valve spring will be of such slim and trim formation as to adapt them to be readily engaged with the spring seat of a valve and to provide the maximum room to remove and replace the spring seat lock or key.

The invention has for a further object to provide a valve lifter of the character stated wherein the spring seat engaging jaws will 65 be of channel formation and arranged with their open sides in opposed relation and wherein the lower flanges and the webs of the jaws will be extended forwardly beyond the upper flanges to provide horizontal and vertical spring seat engaging members, the channel formation of the jaws and the formation of the spring seat engaging members integrally with the lower flanges and webs rendering the jaws strong enough to enable them to 70 be formed trim and slim.

The invention has for a further object to provide a valve lifter of the character stated which will embody a frame having a horizontal arm and a vertical arm extending 80 downwardly from one end of the horizontal arm and of arcuate formation in side elevation, valve head engaging means carried by the other end of the horizontal arm, a lever located below the horizontal arm and pivoted 85 at one end to the lower end of the vertical arm, spring seat engaging means carried by the free end of the lever, a curved arm extending upwardly from the pivoted end of the lever, a hand lever pivoted to the horizontal arm, 90 and a curved link connected to the hand lever and to the upper end of the lever arm, the hand lever, link and lever arm providing means by which the valve seat engaging lever may be swung upwardly to compress the valve 95 spring, and the hand lever, link and lever arm occupying such relative positions after the compression of the spring that they will hold the valve seat engaging lever against accidental downward movement.

The invention has for a further object to provide a valve lifter of the character stated which will embody a ratchet loop surrounding the vertical arm and the lever arm, 5 normally occupying a position which will permit the spring seat engaging lever to be rocked, and adapted to be moved into a position which will hold the lever against accidental rocking movement before the hand 10 lever, link and the lever arm are in operation to hold the valve spring seat engaging lever against movement.

The invention is hereinafter fully described and claimed, and illustrated in the accompanying drawings, wherein:—

Figure 1 is a view partly in vertical section and partly in elevation illustrating the application of the valve lifter ready for actuation to compress the valve spring;

Figure 2 is a similar view illustrating the valve lifter actuated to effect the compression of the spring;

Figure 3 is a sectional view taken on the vertical planes indicated by the line 3—3 of Figure 1.

Figure 4 is a view partly in top plan and partly in horizontal section of a fragmentary portion of the lever and spring seat engaging jaws carried thereby;

Figure 5 is a sectional view taken on the vertical plane indicated by the line 5—5 of Figure 4, and

Figure 6 is a sectional view taken on the horizontal planes indicated by the line 6—6 of Figure 1.

The valve lifter comprises a frame 1 consisting of a horizontal arm 2 and a vertical arm 3. The arm 2 is provided at its front end with valve head engaging means 4; the arm 3, 40 extends downwardly from the rear end of the arm 2. The arm 2 is preferably straight, and the arm 3 is longitudinally curved and has its lower end position directly below the rear end of the arm 2. The frame 1 is made from two flat bars arranged in opposed relation and connected together by rivets 5 and 6. Those portions of the bars constituting the arm 2 are designated 2a, and those portions of the bars constituting the arm 3 are designated 3a.

The arm portions 2a are laterally offset near their front ends to provide a cylindrical socket 7 which extends vertically through the arm 2 and which is provided for the reception of a push rod 8 constituting a part of the valve head engaging means 4. Bolts 9 provided with thumb nuts 10 extend through the arm portions 2a at opposite sides of the socket 7, and provide means by which the sections of the socket may be moved toward each other, 60 or freed for movement away from each other. The movement of the sections of the socket 7 in the direction of each contracts the socket, and the movement of the sections of the socket away from each other expands the socket. When the socket 7 is expanded the

push rod 8 may be adjusted upwardly and downwardly on the arm 2, and when the socket is contracted the push rod is held against accidental movement from its adjusted position.

A lever 11 located below the arm 2, is pivotally connected at its rear end by the rivet 5 to the lower end of the arm 3, and is provided at its front or free end with spring seat engaging means 12. The pivoted end of the lever 11 is located between the arm portions 3a, and curving upwardly from its pivoted end is an arm 13 which is also located between these portions. The lever 11 and its arm 13 are also made from two flat bars, those portions of the bars constituting the lever being designated 11a, and those portions of the bars constituting the lever arm being designated 13a. Washers 14 are mounted upon the rivet 5 at one end of the lever portions 11a, 85 and serve to hold these portions in relatively spaced relation.

A hand lever 15 is pivotally connected at one end to the rear end of the arm 2 by the rivet 6, and normally extends upwardly and rearwardly from its pivot. The hand lever 15 is made of two flat bars designated 15a connected together near their free ends by rivets 16 and 17, and held in spaced relation by washers 18 mounted on these rivets and the rivet 6. A curved link 19 located between the arm portions 3a, is pivotally connected, as at 20, to and between the upper ends of the arm portions 13a and is pivotally connected, as at 21, to and between the lever portions 15a at 100 points close to the pivot 6 of the lever.

The push bar 8 is of hollow formation, and is provided at its lower end with a foot piece 22 of hollow spherical formation and extending in all directions laterally beyond the push bar. A pin 23 having a pointed lower end 24 located at the center of the foot piece 22, is slidably mounted in the push bar 8 to permit the pin to move downwardly and upwardly with respect to the foot piece. The upward and downward movement of the pin 23 is limited by a pin 25 carried by and extending diametrically across the push bar 8 and also extending through a vertical slot 26 in the pin 23. The pin 23 normally occupies a position with its lower end extending below the foot piece 22, and it is yieldingly held in this position by a spring 27 mounted in the push bar 8 between the upper end of the pin and a pin 28 fixed to and extending diametrically across the push bar 8.

The spring seat engaging means 12 comprises jaws 29 secured to the front ends of the lever 11. The jaws 29 are of channel formation and are arranged with their open sides in opposed relation. The jaws 29 comprise shanks 29a which receive and are secured, as at 30, to the front ends of the lever portions 11a. Shanks 29a curve upwardly and forwardly and gradually decrease in width or

vertical dimension from their rear to their front ends. The jaws 29 also comprise spring seat engaging members 29b which extend forwardly from the upper ends of the shanks 29a, and flanges 29c which extend upwardly from the outer edges of the spring seat engaging members. The spring seat engaging members 29b and their flanges 29c form continuations of the lower flanges and the webs 10 of the shanks 29a respectively, and are offset laterally outward with respect to the shanks. The upper flanges of the shanks 29a terminate at the rear ends of the flanges 29c. As the shanks 29a are of channeled formation, and as the spring seat engaging members 29b and their flanges 29c are formed integrally with the shanks, the jaws while slim and trim are so strong as not to yield under the pressure necessary to compress 15 the strongest valve spring. The lever portions 11a hold the jaws 29 in relatively spaced relation ready for application to the spring seat. The distance between the jaws may be varied so as to adapt them for application to spring seats of different sizes 20 through the medium of a bolt 31 passing through the lever portions 11a and the jaw shanks 29a, the head of the bolt contacting with the outer side of one of the shanks, and a nut 32 on the bolt contacting with the outer side of the other shank.

In practice, to adapt the valve lifter for application to a valve, the hand lever 15 is actuated to swing the lever 11 into its lowest 25 adjusted position with respect to the arm 2 if the lever 11 is not already in such position. The pin 23 extends below the foot piece 22, and during the initial phase of the application of the valve lifter the pointed lower end 30 of the pin is engaged with the valve head 33, and during the next final phase of the application of the valve lifter the jaws 29 are engaged with the seat 34 of the valve spring 35. The pin 23 centers the foot piece 22 on the 35 valve head 33, and the jaw members 29b and 29c contact with the lower side and edge, respectively, of the valve spring seat 34. The hand lever 15 now occupies an upwardly and rearwardly inclined position, as shown in 40 Figure 1, and it is swung from this position into a downwardly and rearwardly inclined position, as shown in Figure 2. During this actuation thereof, the hand lever 15 moves between the arm members 3a, the link 19 45 moves between the lever members 15a, and the free end of the lever 11 moves upwardly. During the consequent upward movement of the jaws 29, the foot piece 22 moves downwardly with relation to the pin 23 into contact 50 with the valve head 33. After the foot piece 22 contacts with the valve head 33 the jaws compress the spring 35. During this actuation of the hand lever 15, the link pivot 21 passes from a point above to a point below the lever pivot 6, and the downwardly 55

acting force applied to the lever 11 by the compressed spring 35 acts through the arm 13 and link 19 against the hand lever 15 in a direction which tends to move this lever downwardly. Due thereto, and as the downward movement of the hand lever 15 is limited by the rivet 16 contacting with the rear edge of the link 19, the lever 11 is positively held against accidental downward movement.

The foot piece 22 and the jaws 29 are thus held in their adjusted and spring compressing position. All possibility of the foot piece 22 becoming accidentally displaced from the valve head 33 is prevented by the engagement of the pin 23 with the valve head. There is no possibility of the valve lifter becoming accidentally displaced either while it is being applied or after its application and actuation to effect the compression of the spring. A loop 36 surrounding the vertical arm 3 and the lever arm 13 normally occupies a position close to the pivot 5 of the lever 11, as shown in Figure 1. In this position thereof, the loop 36 will not interfere with the actuation of the lever 11. When conditions are such that the hand lever 15 cannot be swung into its lowest or locking position, the lever 11 is held against downward movement from its adjusted position by the loop 36 which to accomplish this is moved upwardly from its normal position into embracing relation with their arms 3 and 13, as shown in Figure 2. The jaws 29 are slim and trim, may be easily engaged with the spring seat 34, and will when the spring 35 is under compression provide the greatest possible room for the application or removal of the pin or key employed to support the spring seat on the valve stem. The channel formation of the jaws 29 permits them to be made slim and trim and yet strong enough to compress the strongest valve spring. To release the valve lifter for removal from the valve it is only necessary to swing the hand lever 15 upwardly and forwardly.

While I have described the principle of the invention, together with the structure which I now consider the preferred embodiment thereof, it is to be understood that the structure shown is merely illustrative and that such changes may be made, when desired, as fall within the scope of the invention as claimed.

I claim:—

1. In a valve lifter, a frame having a horizontal arm and a vertical arm extending downwardly from one end of the horizontal arm, valve head engaging means carried by the other end of the horizontal arm, a lever located below the horizontal arm and pivoted at one end to the vertical arm, spring seat engaging means carried by the free end of the lever, an arm extending upwardly from the pivoted end of the lever, a hand

lever pivoted at one end to the horizontal arm, and a link pivoted to the upper end of the lever arm and to the hand lever at a point close to the pivot of such lever.

5. 2. In a valve lifter, a frame having a horizontal arm and a vertical arm extending downwardly from one end of the horizontal arm, valve head engaging means carried by the other end of the horizontal arm, a lever located below the horizontal arm and pivoted at one end to the vertical arm, spring seat engaging means carried by the free end of the lever, an arm extending upwardly from the pivoted end of the lever, a hand lever pivoted at one end to the horizontal arm, a link pivoted to the upper end of the lever arm and to the hand lever at a point close to the pivot of such lever, and a loop embracing the vertical arm and the lever arm and movable thereon into a position to hold the lever against movement and into a position to free the lever for movement.

25. 3. In a valve lifter, a frame having a horizontal arm and a vertical arm extending downwardly from the rear end of the horizontal arm, the vertical arm being curved and having its lower end located below said end of the horizontal arm, valve head engaging means carried by the front end of the horizontal arm, a lever located below the horizontal arm and pivoted at its rear end to the lower end of the vertical arm, spring seat engaging means carried by the front end of the lever, an arm curving upwardly from the rear end of the lever, a hand lever pivoted at one end to the rear end of the horizontal arm and normally occupying an upwardly and rearwardly extended position on such arm, and a curved link pivoted to the upper end of the lever arm and to the hand lever at a point above and rearwardly of the pivot of such lever, the lever being adapted to be swung downwardly to swing the lever upwardly and adapted to occupy a downwardly and rearwardly extended position with relation to the horizontal arm with the pivot of the link below its pivot to hold the lever in its upwardly adjusted position.

4. 4. In a valve lifter, a frame having a horizontal arm and a vertical arm extending downwardly from the rear end of the horizontal arm, the vertical arm being curved and having its lower end located below said end of the horizontal arm, valve head engaging means carried by the front end of the horizontal arm, a lever located below the horizontal arm and pivoted at its rear end to the lower end of the vertical arm, spring seat engaging means carried by the front end of the lever, an arm curving upwardly from the rear end of the lever, a hand lever pivoted at one end to the rear end of the horizontal arm and normally occupying an upwardly and rearwardly extended position

on such arm, a curved link pivoted to the upper end of the lever arm and to the hand lever at a point above and rearwardly of the pivot of such lever, the lever being adapted to be swung downwardly to swing the lever upwardly and adapted to occupy a downwardly and rearwardly extended position with relation to the horizontal arm with the pivot of the link below its pivot to hold the lever in its upwardly adjusted position, and a loop embracing the vertical arm and the lever arm and movable thereon into a position to hold the lever against movement and into a position to free the lever for movement.

In testimony whereof I hereunto affix my signature.

IRA J. CLARK.
